(57) **CLAIM**

The ornamental design for a razor blade cartridge, as shown and described.

DESCRIPTION

FIG. 1 is a front elevational view of a razor blade cartridge;
FIG. 2 is a perspective view thereof;
FIG. 3 is a left side elevational view thereof, the right side view being a mirror image;
FIG. 4 is a rear elevational view thereof;
FIG. 5 is an additional front view thereof; and,
FIG. 6 is a top plan view thereof.
The broken lines illustrate the environment of the razor blade cartridge and form no part of the claimed design.
